(57) **CLAIM**

The ornamental design for a multi-function hub, as shown and described.

DESCRIPTION

FIG. 1 is a perspective view of a multi-function hub showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the multi-function hub shown within the area designated as 9 in FIG. 1; and,

FIG. 10 is an enlarged view of the multi-function hub shown within the area designated as 10 in FIG. 2.

The evenly spaced broken lines in the drawings are for the purpose of illustrating portions of the multi-function hub that form no part of the claimed design. The dot-dashed broken lines in FIGS. 1, 2, 9, and 10 show the boundary of the enlarged views and form no part of the claimed design.
